DESIGN FOR A HAT

Matthew P. Hyland, Rye, N. Y.

Application May 26, 1941, Serial No. 101,137

Term of patent 3½ years

To all whom it may concern:

Be it known that I, Matthew P. Hyland, a citizen of the United States, residing in Rye, in the county of Westchester and State of New York, have invented a new, original, and ornamental Design for Hats, of which the following is a specification, reference being had to the accompanying drawing, forming part thereof, in which—

Fig. 1 is a side elevational view of a hat showing my new design;

Fig. 2 is a rear elevational view thereof; and

Fig. 3 is a top view, in undraped position, illustrating the narrow top band in detail.

I claim:

The ornamental design for a hat, as shown.

MATTHEW P. HYLAND.
